(57) **CLAIM**

The ornamental design for a headlight, as shown and described.

DESCRIPTION

FIG. 1 is a perspective view of a first embodiment of a headlight;

FIG. 2 is a front elevation view of FIG. 1;

FIG. 3 is a rear elevation view of FIG. 1;

FIG. 4 is a top plan view of FIG. 1;

FIG. 5 is a bottom plan view of FIG. 1;

FIG. 6 is a right elevation view of FIG. 1, the left elevation view being a mirror image thereof;

FIG. 7 is a perspective view of a second embodiment of the headlight;

FIG. 8 is a front elevation view of FIG. 7;

FIG. 9 is a rear elevation view of FIG. 7;

FIG. 10 is a top plan view of FIG. 7;

FIG. 11 is a bottom plan view of FIG. 7; and,

FIG. 12 is a right elevation view of FIG. 7, the left elevation view being a mirror image thereof.

The broken lines shown in the drawings depict portions of the headlight that form no part of the claimed design.
